UNITED STATES PATENT OFFICE

FRANK McMILLAN, OF GLENELLYN, ILLINOIS, ASSIGNOR, BY MESNE ASSIGNMENTS, TO NATIONAL DROP HEAD PROJECTOR COMPANY, OF FOND DU LAC, WISCONSIN, A CORPORATION OF WISCONSIN.

MOTION-PICTURE MACHINE.

1,326,407.

Specification of Letters Patent. Patented Dec. 30, 1919.

Application filed July 13, 1918, Serial No. 244,707. Renewed May 14, 1919. Serial No. 297,157.

To all whom it may concern:

Be it known that I, FRANK McMILLAN, a citizen of the United States of America, and a resident of Glenellyn, in the county 5 of Dupage, State of Illinois, have invented certain new and useful Improvements in Motion-Picture Machines, of which the following is a specification.

This invention relates to the portable type 10 of motion picture machines and has for its object:—

To provide a simple and substantial structural formation and association of the inclosing casing and film reel magazines 15 adapted to provide a rigid, light and substantial structure adapted to support the different motion picture mechanisms and parts in proper relation, and afford the required features of compactness, strength 20 and lightness required for convenience in transporting the machine from place to place, all as will hereinafter more fully appear.

In the accompanying drawings:—

25 Figure 1 is a side elevation illustrating the general arrangement of parts in the present improvement, the inclosing casing and other parts being shown in section.

Fig. 2, is a transverse sectional elevation 30 on line X²—X² Fig. 1, with the middle portions of the magazines and accessories removed to show the film feeding mechanism in front of said magazines.

Fig. 3, is a detail perspective view of one 35 of the skeleton bracing frames of the structure.

Like reference numerals indicate like parts in the several views.

Referring to the drawings, 1 designates 40 the main inclosing casing of the machine, preferably of the rectangular shell form shown, and having a portion of its front wall formed as a separate part or section 2 and movable in relation to the main portion 45 of the main casing. In the present structure said movable section 2 constitutes the greater part of the front portion of the casing 1, is hinged at its lower end to said casing by a hinge connection 2' as shown, and 50 forms the supporting means for the film feeding mechanism of the machine, so that when said movable section 2 is opened on its hinged connection the film feeding mech-

anism will move therewith into a fully exposed condition convenient of access for the 55 usual manual manipulations of the picture film required previous to, during and subsequent to a display of the pictures of the film. In addition to the above described construction of the main casing, the rear 60 wall thereof is formed with a central vertical opening or passage 3 adapted to receive the adjustable illuminating means herein-after described.

2' designates a latch mechanism for holding the movable section 2 aforesaid in a closed and operative position.

4, 4 designate counterpart skeleton bracing frames, of structural metal, secured in a longitudinal direction and in transversely 70 spaced relation in the interior of the main casing 1, and at equal distances from the longitudinal center of same. The bracing frames 4, 4 are preferably of the rectangular yoke shape shown, and are adapted to 75 provide the required stability and strength to support the various parts and mechanisms of the machine in proper operative relation, as well as to effectively brace the 80 walls of the main casing 1 and permit the use of thin and light plate material in the formation of such walls.

5, 5 designate counterpart reel casings, preferably of the open ended cup form shown, with their inner and fixed ends or 85 heads arranged in transversely spaced relation, and with the separating space corresponding with the transverse width of the aforesaid vertical rear opening or passage 3 of the main casing 1 to provide a central 90 chamber or passage in the machine for the passage of the light beams from the rearwardly arranged source of illumination, as well as a containing space for the inner portion of the film feeding mechanism and 95 for the lamp house containing said source of illumination. In the present improvement the inner portions of the magazines 5, 5 are arranged within the bracing members 4, 4 aforesaid, and are secured thereto by 100 rivets or like fastening means, while the open outer portions of said magazines have bearings in flanged orifices in the side walls of the casing 1 and project outwardly therefrom to receive the hinged doors now to be 105 described.

- 6, 6 designate individual doors, preferably of a shallow cup form, hinged to the side walls of the casing 1 and fitting over the outwardly projecting end portions of 5 the magazines 5, 5, said cup shape doors being provided with beaded marginal flanges 6' adapted to bear against the side walls of the casing 1, to provide a durable and substantial construction of parts.
- 10 7 designates the carrying shaft of the film supply and take-up reels of the machine, the detail construction and arrangement of which are set forth in a companion application for Letters Patent, Serial No. 244,796.
- 15 8 designates a pulley mounted on the central portion of the reel carrying shaft 7 and having operative connection with the film feeding mechanism of the machine.
- 9 designates the supporting frame of the 20 film feeding and guiding mechanism of the machine, and which in the present structure is secured to and is movable with the hinged section 2 of the main casing heretofore described.
- 25 10 designates the objective of the motion picture machine, also mounted on the hinged section 2 of the main casing in proper operative relation to the film feeding and guiding means and associated light controlling means of the machine.
- 30 11 designates the primary shaft of the film feeding mechanism, journaled transversely in the supporting frame 9 aforesaid, and having the usual intermittent and continuous gearing connections with the intermittent film feeding sprocket drum 12 and carrying shaft 13 of the light controlling shutter of the machine.
- 14 designates a friction or like driven 40 wheel secured to the primary shaft 11, and having operative engagement with a similar driving wheel 15 carried on the forward end of a shaft 16 arranged longitudinally in the heretofore described central space of the machine.
- 45 17 designates a pulley mounted on the primary shaft 11 and having an endless belt connection 18 with the pulley 8 of the reel carrying shaft 7 aforesaid.
- 50 19, 20 designate the film supply and film take-up sprocket drums of the machine, fixed on the respective ends of the primary shaft 11 in line with the film supply and film take-up reels when the same are in position 55 in the magazines 5, 5.
- 21 designates an electric or like motor by which the machine is driven, arranged in the rear and lower portion of the central space of the machine, as shown, and having gearing connection 22 with the rear end of the longitudinally arranged shaft 16 aforesaid. With the arrangement of the mechanism so far described, as the hinged section 2 of the main casing 1 is lowered to an open position, it carries with it the film feeding and guiding mechanism to a position in which said parts, as well as the entry and exit openings of the reel magazines 5, 5 are readily accessible for the usual changes and manipulations of the picture 70 film in changing or replacing the same.
- 23 designates a trackway secured longitudinally to the inner fixed wall of a magazine 5 aforesaid, and adapted to receive and guide a sliding bar 24.
- 75 25 designates an inclosing casing containing the condenser lens of the light system of the machine, and secured to the rear end of the sliding bar 24 so as to be adjustable therewith.
- 26 designates a lamp house or casing secured to the rear end of the lens containing casing 25 aforesaid, by vertically arranged inter-engaging flanges 27, so as to be capable of independent vertical adjustment in 80 relation to said casing 25, in effecting a proper adjustment of the machine for actual use.
- The detail construction and arrangement of the condenser lens casing and lamp house 90 and the adjustments of the same above described, are set forth in detail and claimed in a companion application for Letters Patent, Serial No. 244,708, and no claim thereto is made in the present case.
- 95 Having thus fully described my said invention, what I claim as new and desire to secure by Letters Patent, is:—
1. In a portable motion picture machine, an inclosing housing comprising a pair of 100 rectangular structural metal bracing frames arranged in spaced transverse relation, and a rectangular casing of sheet material secured to said frames, with its width greater than the transverse spacing of said frames 105 to provide central and side containing spaces for the mechanisms of the machine, substantially as set forth.
2. In a portable motion picture machine, an inclosing housing comprising a pair of 110 structural metal bracing frames of a rectangular yoke shape arranged in spaced transverse relation, and a rectangular casing of sheet material secured to said frames, with its width greater than the transverse spacing of said frames to provide central and side containing spaces for the mechanisms of the machine, substantially as set forth.
- 115 3. In a portable motion picture machine, an inclosing housing comprising a pair of 120 rectangular structural metal bracing frames arranged in spaced transverse relation, a rectangular casing of sheet material secured to said frames, and a pair of film reel magazines arranged in spaced transverse relation and secured to said frames, substantially as set forth.
- 125 4. In a portable motion picture machine, an inclosing housing comprising a pair of structural metal bracing frames of a rec- 130

tangular yoke shape arranged in spaced transverse relation, a rectangular casing of sheet material secured to said frames, and a pair of film reel magazines arranged in spaced transverse relation and secured to said frames, substantially as set forth.

5. In a portable motion picture machine, an inclosing housing comprising a pair of rectangular structural metal bracing frames arranged in spaced transverse relation, a rectangular casing of sheet material secured to said frames, and a pair of film reel magazines of a cup form secured in spaced relation to each other to said frames, the open

10 ends of said magazines extending out beyond the side walls of the casing, and removable doors associated with said open ends of the magazines, substantially as set forth.

15 6. In a portable motion picture machine, an inclosing housing comprising a pair of rectangular structural metal bracing frames arranged in spaced transverse relation, a rectangular casing of sheet material secured to said frame, and a pair of film reel magazines of a cup form secured in spaced relation to each other to said frames, the open ends of said magazines extending out through flanged openings in the side walls

20 of said casing, and removable doors associated with said open ends of the magazines, substantially as set forth.

25 7. In a portable motion picture machine an inclosing housing comprising a pair of rectangular structural metal bracing frames of a rectangular yoke shape arranged in spaced transverse relation, a rectangular

30 casing of sheet material secured to said

frames, and film reel magazines of cup form secured in spaced relation to each other to said frames, the open ends of said magazines extending out through flanged openings in the side walls of said casing, and removable doors associated with said open ends of the magazines, substantially as set forth.

40 8. In a portable motion picture machine an inclosing housing comprising a pair of rectangular structural metal bracing frames arranged in spaced transverse relation, a rectangular casing of sheet material secured to said frames, and a pair of film reel magazines of a cup form secured in spaced relation to each other to said frames, the open ends of said magazines extending out beyond the side walls of the casing, and removable doors of a shallow cup form associated with said open ends of the magazines,

45 substantially as set forth.

9. In a portable motion picture machine, an inclosing housing comprising a pair of rectangular structural metal bracing frames arranged in spaced transverse relation, a rectangular casing of sheet material secured to said frames, and a pair of film reel magazines of a cup form secured in spaced relation to each other to said frames, the open ends of said magazines extending out beyond the side walls of the casing, and removable doors of a shallow cup form and having marginal stiffening rims associated with said open ends of the magazines, substantially as set forth.

60 70 Signed at Santa Cruz, Cal., this 3d day of June, 1918.

FRANK McMILLAN.
